UNITED STATES PATENT OFFICE.

JAMES L. AMES, OF NEWTON, KANSAS.

TRAFFIC-SIGNAL.

1,250,265.

Specification of Letters Patent. Patented Dec. 18, 1917.

Application filed March 29, 1917. Serial No. 158,210.

To all whom it may concern:

Be it known that I, JAMES L. AMES, a citizen of the United States, residing at Newton, in the county of Harvey and State of Kansas, have invented new and useful Improvements in Traffic-Signals, of which the following is a specification.

This invention relates to traffic signals, the object in view being to provide a signal capable of being applied to the present day automobile or motor vehicle and embodying means whereby signaling members may be selectively shifted from a concealed position to a signaling position to indicate when the operator of the vehicle intends to make a turn to the right or to the left.

One of the principal objects of the invention is to so construct and arrange the parts of the signaling apparatus as a whole, that either one of the signaling members may be individually operated, independently of the other, and automatically locked in its signaling position, where it will remain until unlocked by the operator and permitted to return by gravity to its concealed position, at the same time preventing the rattling thereof.

With the above and other objects in view, the invention consists in the novel construction, combination and arrangement of parts, herein fully described, illustrated and claimed.

In the accompanying drawing:—

Fig. 1 is a fragmentary plan view of a sufficient portion of a motor vehicle to illustrate the signaling apparatus in its applied relation thereto.

Fig. 2 is a perspective view of the signaling apparatus detached.

Fig. 3 is a vertical sectional view of the same.

Fig. 4 is a fragmentary section on the line 4—4 of Fig. 1.

Fig. 5 is a fragmentary horizontal section taken in line with the pivot of the signaling members.

Fig. 6 is a fragmentary section on the line 6—6 of Fig. 3.

The signaling apparatus contemplated in this invention comprises a vertically elongated housing 1 of sufficient dimensions to contain a plurality of signaling members 2 and 3, the housing 1 being open at its outer side as indicated at 4 to allow the sig-

naling members to be shifted into said housing and to be projected therefrom in the manner indicated in Fig. 3.

Two of such signaling members are illustrated in the drawings, one containing the word "left" and the other containing the word "right," although other symbols of direction may be employed. The signaling members 2 and 3 are mounted upon a common pivot 5 shown in the form of a bolt inserted through the opposite side walls of the housing 1 and through the inner and upper end portions of the signaling members 2 and 3. The housing 1 is provided on the inner side thereof with an L-shaped clamp 6 adapted to be slipped over the side wall 7 of a vehicle as shown in Fig. 1 and fastened by means of a clamping screw 8. Adjacent to its lower end the housing 1 is formed with a bolt hole 9 to receive a bolt which may be also inserted through the side member 7 of the vehicle body, the housing 1 being thus rigidly fastened to the body.

Secured to the instrument board 10 of the vehicle body is a support 11 shown as comprising the substantially parallel bars 12 and 13 and the ends clamps 14 which are substantially U-shaped and open at their upper sides. The clamps 14 are adapted to fit under and embrace the instrument board 10, being secured thereto by clamping screws 15 as shown in Fig. 4.

Journaled in the parallel bars 12 and 13 of the support 11 and extending therethrough are parallel shafts 16 each of which is provided at its rear end with a hand grip 17 shown preferably in the form of a wheel, and having rigidly secured thereto between the bars 12 and 13, signal operating arms 18. Rods 19 are pivotally attached at one end to the arms 18 and are pivotally attached at their opposite extremities to the upper extremities of the signaling members 2 and 3 as shown in Fig. 3, the rods 19 working through an opening 20 in the inside wall of the housing 1.

Arranged within the lower portion of the housing 1 are substantially U-shaped spring clips 21 adapted to receive and engage the adjacent edges of the signaling members 2 and 3 when the latter are within the housing 1 and concealed. The clips 21 frictionally hold the signaling members and prevent the same from rattling. They are not suffi-

2
ciently strong however to prevent the signaling members from being shifted to their projecting or signaling positions.

By reference to Fig. 3 it will be noted that the outer extremities of the rods 19 are deflected downwardly as shown at 22 so that the points of attachment 23 of said rods to the arms 18 will pass below a line extended through the shafts 16 and the points of attachment 24 where said rods 19 connect to the signaling members. The result of the arrangement just referred to is that each of the signaling members 2 and 3 is automatically locked in its signaling position and remains so locked until the operator grasps the respective hand grip 17 and swings the respective operating arm 18 in a direction to restore the signaling member to its concealed position.

Only one bolt is required to fasten all of the signaling apparatus to a motor vehicle, the remainder of the device is clamped to the side of the body and to the instrument board as hereinabove explained and as will appear from the accompanying drawings.

I claim:

1. In a traffic signal, the combination of a plurality of pivoted signaling members pivotally mounted therein, a bearing support, a plurality of signal operating shafts journaled in said bearing support, arms extending from said shafts, and connecting rods terminally attached to said arms at one end and terminally attached at their opposite extremities to said signaling mem-

bers, the extremities of said rods which connect with said operating arms being deflected so as to partially embrace and contact with their respective operating shafts and pass beyond a line extended through the operating shafts and the points of attachment between said rods and signaling members, whereby each signaling member is automatically locked in its signaling position.

2. In a traffic signal, the combination of a housing, a plurality of signaling members, a bearing support, a plurality of signal operating shafts journaled in said bearing support, arms extending from said shafts, connecting rods terminally attached to said arms at one end and terminally attached at their opposite extremities to said signaling members, the extremities of said rods which connect with said operating arms being deflected so as to partially embrace and contact with their respective operating shafts and pass beyond a line extended through the operating shafts and the points of attachment between said rods and signaling members, whereby each signaling member is automatically locked in its signaling position, and spring clips which frictionally engage and retain said signaling members in their housed positions.

In testimony whereof I affix my signature in presence of two witnesses.

JAMES L. AMES.
